US00D649123S

(12) **United States Design Patent**
Jacoby et al.

(10) **Patent No.:** **US D649,123 S**
(45) **Date of Patent:** **** Nov. 22, 2011**

(54) **LOAD CONTROL DEVICE**

(75) Inventors: **Elliot G. Jacoby**, Glenside, PA (US);
Erica L. Clymer, Nazareth, PA (US);
Jason C. Killo, Emmaus, PA (US);
Matthew Philip McDonald,
Phoenixville, PA (US); **Noel Mayo**,
Philadelphia, PA (US)

(73) Assignee: **Lutron Electronics Co., Inc.**,
Coopersburg, PA (US)

(**) Term: **14 Years**

(21) Appl. No.: **29/378,451**

(22) Filed: **Nov. 4, 2010**

(51) **LOC (9) Cl.** **13-03**

(52) **U.S. Cl.** **D13/164; D13/171**

(58) **Field of Classification Search** ..... **D13/162, D13/164, 171, 174; 200/5 R, 5 A, 302.2, 200/520, 530, 293, 296, 308, 310, 314, 329, 200/341; 307/139, 157; 315/209 R, 224, 315/246, 291, 294, 295**

See application file for complete search history.

(57) **CLAIM**

We claim the ornamental design for a load control device, as shown and described.

DESCRIPTION

FIG. 1 is a perspective view of a load control device according to a first embodiment of our new design.

FIG. 2 is a front view thereof.

FIG. 3 is a left side view thereof.

FIG. 4 is a right side view thereof.

FIG. 5 is a top view thereof; and,

FIG. 6 is a bottom view thereof.

The portions of the drawings appearing in broken line are for environment only and do not form a part of the claimed design. The rear views form no part of the design and are omitted.

1 Claim, 4 Drawing Sheets
